(57) **CLAIM**

The ornamental design for a click button for hand torch, as shown and described.

DESCRIPTION

FIG. 1 is a left rear perspective view of a click button for hand torch disengaged from receiving member showing our design;

FIG. 2 is a right front perspective view of the click button for hand torch of FIG. 1;

FIG. 3 is a bottom plan view of the click button for hand torch of FIG. 1;

FIG. 4 is a left side view of the click button for hand torch of FIG. 1;

FIG. 5 is a top plan view of the click button for hand torch of FIG. 1;

FIG. 6 is a right side view of the click button for hand torch of FIG. 1;

FIG. 7 is a front elevational view of the click button for hand torch of FIG. 1;

FIG. 8 is a rear elevational view of the click button for hand torch of FIG. 1;

FIG. 9 is a left rear perspective view of the click button for hand torch engaged to receiving member showing our design;

FIG. 10 is a right front perspective view of the click button for hand torch of FIG. 9;

FIG. 11 is a bottom plan view of the click button for hand torch of FIG. 9;

FIG. 12 is a left side view of the click button for hand torch of FIG. 9;

FIG. 13 is a top plan view of the click button for hand torch of FIG. 9;

FIG. 14 is a right side view of the click button for hand torch of FIG. 9;

FIG. 15 is a front elevational view of the click button for hand torch of FIG. 9; and,

FIG. 16 is a rear elevational view of the click button for hand torch of FIG. 9.
